(57)

CLAIM

The ornamental design for a flange coupling for process cartridge for image forming apparatus, as shown and described.

DESCRIPTION

1. Flange coupling for process cartridge for image forming apparatus

1.1 : Front

1.2 : Back

1.3 : Top

1.4 : Bottom

1.5 : Left

1.6 : Right

1.7 : Perspective

The broken lines represent portions of the flange coupling for process cartridge for image forming apparatus that form no part of the claimed design.

1 Claim, 7 Drawing Sheets
